UNITED STATES PATENT OFFICE

2,243,307

EVAPORATOR

Jackson Lee Campbell, Wichita, Kans., assignor to
 Sears, Roebuck and Co., Chicago, Ill., a corpora-
 tion of New York

Original application September 20, 1929, Serial
 No. 394,011. Divided and this application June
 6, 1939, Serial No. 277,616

5 Claims. (Cl. 62—126)

This application is a division of my co-pending application Serial No. 394,011, filed September 20, 1929, now matured into Patent No. 2,210,898.

My invention relates to refrigeration apparatus and has to do more particularly with an evaporator designed especially for use in a continuous absorption system, although, as will be readily understood by those skilled in the art, my invention is not limited to such a system of refrigeration.

A particular object of my invention is to provide an evaporator which will efficiently effect heat transfer from a liquefied refrigerant in the presence of an inert gas.

Another object is to provide a device of the type referred to which will be simple in construction, easy to fabricate, and, in general, entirely satisfactory for the purposes desired.

Referring now to the drawing forming a part of this specification and illustrating a preferred embodiment of my invention:

Fig. 1 is a vertical sectional view of an evaporator embodying my invention, certain associated parts being shown fragmentarily, and

Fig. 2 is a similar view taken substantially along the line 2—2 of Fig. 1.

Numeral 10 represents generally a refrigerator cabinet having a food compartment 12 in which is disposed an evaporator, indicated generally by the numeral 15, embodying my invention.

The evaporator comprises a substantially rectangular casing 16 of metal or other suitable material of good heat conductivity, heat exchange fins 18 extending around the top, bottom and side walls thereof. The evaporator may have an open ended compartment 20 for the reception of ice trays or other receptacles.

A conduit 21 leading from a condenser or other suitable source of liquid refrigerant extends through the top wall of the evaporator and discharges into a well 23. This well, as shown in Fig. 1, may be formed in part by a side wall of the evaporator. An overflow spout 25 communicates with the upper portion of well 23 and discharges onto the uppermost of a series of baffle plates 27 arranged in an evaporating chamber 28 laterally adjacent the compartment 20. These baffle plates are alternately inclined in opposite directions and are provided with outlet openings 30 adjacent their lower ends, so that liquid which is discharged from the well 23 onto the uppermost baffle plate 27 flows downwardly, then through the orifice 30, and then similarly from one baffle plate to another until it reaches the bottom of the evaporating chamber 28. Com-

municating with the bottom of the evaporating chamber 28 is a discharge conduit 32.

A conduit 35, concentric with the conduit 32 and larger than the same, communicates with a chamber or flue 37, the upper portion of which discharges into the evaporating chamber 28.

The operation of the device just described is substantially as follows:

Liquid refrigerant is introduced, as from a condenser (not shown), through conduit 21 into the well 23 while hydrogen or other inert gas is introduced through conduit 35 into the flue 37 and thence into the evaporating chamber 28, where it mingles with the liquid refrigerant which is poured into the evaporating chamber through overflow spout 25. The reservoir 23 provides a substantially constant supply of refrigerant to the evaporator plates and tends to prevent flooding thereof. The inert gas, admixed with the liquid refrigerant, flows successively down the plates 27 until it reaches the bottom of the chamber, evaporation taking place in the course of the flow until the mixture of inert gas and refrigerant gases is discharged through the conduit 32, whence it passes into a suitable absorber where the refrigerant will be absorbed and the inert gas will be returned to the evaporator via conduit 35.

The inert gas operates within the evaporator according to Dalton's law of partial pressures, which is now well understood. According to this law, the partial pressure of any gas in a mixture of gases in a closed receptacle is the same as that gas would have exerted alone. Hence, when liquid refrigerant, such as ammonia, is introduced into the evaporating chamber in the presence of hydrogen or other inert gas, there will immediately be a tendency for the liquid to evaporate and thus exert its own vapor pressure, keeping the total pressure constant. Thus, the presence of the inert gas enhances the evaporation of the refrigerant. Since the bottom of the evaporating chamber is open to discharge, the maximum vapor pressure of the refrigerant will never be reached and hence a condition of equilibrium can never be obtained and the evaporation will continue at a maximum rate. Evaporation is also enhanced by the circuitous route which must be traveled by the liquid refrigerant in passing from the top to the bottom of the evaporating chamber. There is thus established a continuous circulation through the evaporator of inert gas admixed with refrigerant, the combined gases being discharged at the bottom through the conduit 32.

Various modifications and variations coming within the spirit of my invention may suggest themselves to those skilled in the art, and hence I do not wish to be restricted to the specific form shown or uses mentioned, except to the extent indicated in the appended claims, which are to be interpreted as broadly as the state of the art will permit.

I claim:

1. In combination in a refrigeration unit, a 10 casing having a well formed integrally therewith, means for introducing liquid refrigerant into said well and overflow means discharging therefrom, an evaporating chamber in said casing having means positioned to receive refrigerant from said overflow means and formed to provide a tortuous evaporating surface from top to bottom of said chamber, means for conducting an inert gas to the top of said chamber, and a conduit for discharging mixed refrigerant 20 and inert gas from said chamber and constituting the sole outlet therefrom, said gas conducting means and said discharge means being disposed in heat exchange relation.

2. A combination as defined in claim 1, where- 25 in the means for conducting an inert gas to the top of the chamber consists of a flue having one wall in common with said well and a wall in common with said evaporating chamber.

3. In combination, in a refrigeration unit, a 30 substantially rectangular casing comprising a substantially rectangular evaporating chamber having a plurality of vertically spaced apertured plates, alternate plates being oppositely tilted from horizontal position to promote the flow and evaporation of refrigerant, a substantially rectangular cooling chamber in heat exchange relation to said evaporating chamber, means for feeding refrigerant liquid and means for feeding inert gas to the uppermost of said plates, and 35 means for discharging mixed refrigerant and inert gas from said refrigerant chamber.

4. In combination, in a refrigeration unit, a substantially rectangular casing comprising a substantially rectangular evaporating chamber having a plurality of vertically spaced apertured plates, alternate plates being oppositely tilted from horizontal position to promote the flow and evaporation of refrigerant, a substantially rectangular cooling chamber in heat exchange relation to said evaporating chamber, a refrigerant well formed integrally with said evaporating chamber, overflow means for conducting liquid refrigerant from said well to the uppermost of said plates, a flue for inert gas disposed between said well and the refrigerant chamber and discharging to the space above the uppermost of said plates, and means for discharging mixed refrigerant and inert gas from the lower portion of said refrigerant chamber.

5. In combination, in a refrigeration unit, a substantially rectangular casing comprising a substantially rectangular evaporating chamber having a plurality of vertically spaced apertured plates, alternate plates being oppositely tilted from horizontal position to promote the flow and evaporation of refrigerant, a substantially rectangular cooling chamber in heat exchange relation to said evaporating chamber, a refrigerant well formed integrally with said evaporating chamber, overflow means for conducting liquid refrigerant from said well to the uppermost of said plates, a flue for inert gas disposed between said well and the refrigerant chamber and discharging to the space above the uppermost of said plates, means for discharging mixed refrigerant and inert gas from the lower portion of said refrigerant chamber, said discharge means constituting the sole outlet from said evaporating chamber, and means in heat exchange relation with said discharge means for conducting inert gas to said flue.

JACKSON LEE CAMPBELL.
